UNITED STATES PATENT OFFICE

JOHN W. NEWBERY, OF ROCKVILLE CENTER, NEW YORK

LIQUID-FUEL BURNER

Application filed December 13, 1929. Serial No. 413,748.

My present invention relates to liquid fuel burners and more particularly to the type of burner shown and described in United States Patent No. 1,660,348, issued to me February 5 28, 1928, which type is particularly adapted and intended for use in the fire-box of a range.

It has for its general object the provision of means adapted to cause the combustion of the gaseous fuel to be more completely localized and the heat therefrom better concentrated upon elements provided for its storage, whereby the loss of temperature by convection is reduced with a corresponding conservation of heat for useful radiation.

With the above object in view, together with other minor objects hereinafter referred to, my invention consists in the provision in a burner structure including a pair of horizontal baffle plates at its top, from which depend heat storage elements, of a plurality of vertical baffles radially disposed between the rims of said horizontal plates, whereby the passage of gaseous currents from the combustion flues are deflected and diverted and 25 their upward passage and ultimate escape flue-ward are delayed.

By thus delaying the flow of combustion gases and insuring their directional flow, their contact with the heat retaining elements 30 is prolonged effectively and the efficiency of their indirect application to oven-heating is increased. By horizontally and also vertically baffling the ascending currents, eddy currents are avoided in great measure, whereby 35 by more even and constant application of heat is obtainable therefrom in those parts of the burner intended to be heated thereby.

In the preferred structural embodiment of my invention illustrated in the accompanying drawings, Figure 1 is a perspective view 40 of a twin burner, parts of one burner being removed to show those underlying them; Figure 2 is a view in vertical mid-section through a single burner; and Figure 3 is a plan view 45 of the burner tops.

In the several views, the numerals indicate like parts. 1 is the base. 2, 3 and 4 are circular troughs therein. 5, 6, 7 and 8 are 50 perforated tubular elements, concentrically nested, seated in recesses upon the inner faces

of the sides of the troughs. 9, 10 and 11 are guides for locating the tubular elements to their seats. 12 is an annular horizontal baffle plate having flue-holes 13 therethrough, downwardly tapered bars 14 depending 55 therefrom and the radially arranged vertical baffles 15. This annular baffle seats upon the tops of the tubular elements 6, 7, with its bars 14 projecting downwardly therebetween. 16 is a horizontal baffle whose diameter is 60 substantially that of the baffle 12.

Baffle 16 comprises a central disk 17, adapted to seat upon the top of the tubular element 8 and close same, and a skeleton frame 18 connecting the central disk with the outer 65 rim of the plate, the skeleton construction affording flue openings 19, 20, between the upwardly projecting, radially arranged, vertical baffles 21. The baffle 16 has the tapered bars 22 depending from it, which project 70 downwardly between the adjacent walls of the tubular elements 7 and 8.

The base 1 is adjustably supported by a telescopic column 23 upon the tripod 24. Each set of troughs has an oil supply connection 75 25.

The method of operation includes the supply of air through the open bottom of the central tube 8 and through its perforated walls to the combustion chamber over trough 4; and through the perforated wall of tubular element 7 to the combustion chamber over trough 3, which chamber is also supplied with air through the perforated wall of tubular element 6 which separates it from the combustion chamber next it and over trough 2, the outer combustion chamber over trough 2 being supplied by air through the perforations in wall 5. The burning vapor ascending from trough 4 heats the bars 22; the vapor 80 from trough 3 heats the bars 14; and the vapor from trough 2 serves to preheat the air caused to be drawn through the other chambers by the suction of the air ascending in the central tube, which passes out through 85 its wall 8 and between the horizontal baffles 12 and 16 and between the vertical baffles 15. The upward draft caused by the outer tubular element 5, flues 13, 19 and 20, also 90 serves to supplement the suction of air across 95 100

the bars 14, 22, with the combined effect of causing them to become incandescent, thus centralizing the thermal units in the bars. As will be understood from Patent No. 5 1,660,348, above referred to, the preferred utility of this burner is as a heating unit in a range, where it is desirable that the maximum quantity of heat units be concentrated adjacent the oven when the latter is to be used.

10 My improved burner heightens this effect in marked degree in comparison with the burner of said patent due to the provision of the radially disposed vertical baffles intermediate the pair of horizontal baffles there-in provided, and of the similarly disposed vertical baffles upon the top of the upper horizontal baffle, with which the plates of the range or the bottom of a cooking utensil 15 thereon co-operate to furnish additional directional channels, so that the combined effect is to cause the flow of the combustion gases through more protracted channels and thereby delay appreciably the rate of passage of 20 the gases from the burner to the chimney.

25 Having thus described my invention and the principle of its operation, I claim:

1. A liquid fuel burner comprising a plurality of foraminous concentric tubular elements vertically disposed and spaced apart; a 30 base provided with fuel troughs therein, said troughs being located beneath the spaces between said tubular elements, and constituting therewith a plurality of combustion chambers; a baffle plate extending above and closing the central tubular member and above the combustion chambers; a second baffle plate extending above and closing one of said combustion chambers; and a series of vertically 35 disposed baffles extending radially intermediate said baffle-plates.

2. A liquid fuel burner comprising a plurality of foraminous tubular elements vertically disposed and concentrically spaced 40 apart; a base common thereto and provided with circular fuel troughs therein, the opposite walls of a pair of tubular elements forming a combustion chamber over each trough; a horizontal baffle extending over one combustion 45 chamber; a second horizontal baffle extending over an adjacent combustion chamber; and a plurality of radially disposed vertical baffles extending between said horizontal baffles.

55 3. A liquid fuel burner comprising a plurality of foraminous tubular elements; a base common thereto and adapted to seat said elements concentrically; concentric fuel troughs in said base disposed beneath adjacent tubular elements, whereby a combustion chamber is provided above each trough; an annular plate seated on the tops of two of the tubular elements and forming the top of a combustion chamber between said pair of tubular elements; a plurality of radially disposed ver-

tical baffles upon the upper surface of said plate; a second plate seated on the top of the central tubular element and extending laterally above the first plate; and a plurality of radially disposed vertical baffles upon the upper face of said second plate.

4. A liquid fuel burner comprising a plurality of foraminous tubular elements; a base common thereto and adapted to seat said elements concentrically; concentric fuel troughs in said base disposed beneath adjacent tubular elements, whereby a combustion chamber is provided above each trough; an annular plate seated on the tops of two of the tubular elements and forming the top of a combustion chamber between said pair of tubular elements; a plurality of radially disposed vertical baffles upon the upper surface of said plate; a second plate seated on the top of the central tubular element and extending laterally above the first plate; a plurality of flues in said first plate and a plurality of flues in said second plate; and a plurality of radially disposed vertical baffles upon the upper face of said second plate.

5. A liquid fuel burner comprising a plurality of foraminous tubular elements; a base common thereto and adapted to seat said elements concentrically; concentric fuel troughs in said base disposed beneath adjacent tubular elements, whereby a combustion chamber is provided above each trough; an annular plate seated on the tops of two of the tubular elements and forming the top of a combustion chamber between said pair of tubular elements; a plurality of tapered bars projecting downwardly from said plate into said chamber; a plurality of radially disposed vertical baffles upon the upper surface of said plate; a second plate seated on the top of the central tubular element and extending laterally above the first plate; a plurality of tapered bars depending from said second plate into another combustion chamber; a plurality of flues in said first plate and a plurality of flues in said second plate; and a plurality of radially disposed vertical baffles upon the upper face of said second plate.

JOHN W. NEWBERY.
